UNITED STATES PATENT OFFICE.

WADE HAMPTON DE FONTAINE, JR., OF PERTH AMBOY, NEW JERSEY.

KEROSENE-CARBURETER.

1,176,816.

Specification of Letters Patent. Patented Mar. 28, 1916.

Application filed May 28, 1914, Serial No. 841,562. Renewed February 16, 1916. Serial No. 78,779.

To all whom it may concern:

Be it known that I, WADE HAMPTON DE FONTAINE, Jr., a citizen of the United States, and a resident of Perth Amboy, in the county of Middlesex and State of New Jersey, have invented certain new and useful Improvements in Kerosene-Carbureters, of which the following is a specification.

My invention relates to carbureters designed to form a combustible mixture from air and a liquid fuel to be used in an internal combustion engine, and particularly to carbureters designed for use with the power systems of automobiles and similar self-propelled vehicles.

The objects of my invention are to provide improved regulating and controlling mechanism for maintaining a constant or an approximately constant proportion of the constituents of the combustible mixture; to provide improved means for heating and vaporizing the air and liquid fuel used to form the combustible mixture and for heating the combustible mixture after it has been formed; and to provide an improved carbureter designed to use kerosene as a liquid fuel and one which will be simple in construction, easy to manufacture, and effective for the purpose for which it is designed.

With the above and other objects in view, my invention consists in the improved carbureter illustrated in the accompanying drawing, described in the following specification, and claimed in the clauses of the concluding claim, and in such variations and modifications thereof as will be obvious to those skilled in the art to which my invention relates.

In the accompanying drawing wherein the preferred embodiment of my invention is illustrated, and wherein the same reference numerals are employed to designate like parts in the several figures; Figure 1 is a view of my improved carbureter mainly in section upon a vertical central plane; Fig. 2 is a fragmentary view taken upon a horizontal plane indicated by the line 2—2, Fig. 1, looking down; Fig. 3 is a view showing my improved carbureter in plan; Fig. 4 is a view showing a fuel controlling valve employed in my carbureter, in perspective, and Fig. 5 is a fragmentary view taken upon a vertical transverse plane indicated

by the line 5, 5, Fig. 1, looking toward the right.

Referring to the drawing, the reference numeral 5 designates the exterior wall of the body portion or casing of my improved carbureter, and 6 designates the inner wall thereof, the lower portion of which inner wall is made conical in form as shown at 7 and the upper portion of which is so shaped as to provide a carbureting chamber 8 within which air and a heated or vaporized liquid fuel are mixed to provide a combustible mixture. Two intersecting conduits are shown at 9 the walls of which merge with the inner wall 6 and which conduits extend transverse to the carbureting chamber and are in the path of the combustible mixture as it flows toward the engine with which the carbureter is used.

The outer and inner walls 5 and 6 are spaced apart from one another to thereby provide an intervening heating chamber 10 with which suitable pipes are connected at 11, and through which pipes and heating chamber a portion of the exhaust gases from the engine with which the carbureter is used may be made to flow to thereby heat the carbureter as will be understood. The ends of the transverse conduits 9 communicate with the heating chamber herein referred to, as shown, and a part of the heating medium flows through said conduits, from which it follows that the mixture within the carbureting chamber is heated both from without the same and by contact with said conduits.

The reference numeral 12 designates a hollow shell conical in form throughout the greater portion of its length, which shell fits within the lower conical portion of the inner wall and is provided with a flange 13 at its lower end whereby it may be secured in place as by means of a screw or screws 14. The upper portion of this shell is spaced slightly from the conical portion 7 of the inner wall 6, as shown in Fig. 1, to thereby provide an intervening fuel chamber which is annular in cross section because of the annular cross-sections of the wall 7 and shell 12, and within which fuel chamber the liquid fuel is extended and forms a thin film between the shell and wall, so that the fuel within said chamber may be effectively heated, the lower end of the space between

said parts being in communication with an annular groove 15 which in turn communicates with a fuel supply passage 16 provided in the carbureter casing and through which 5 fuel is supplied to the fuel chamber.

The upper end of the shell 12 forms a valve seat for the air inlet valve 17 of the carbureter, and the air flows to said valve and past the same and into the carbureting 10 chamber through the interior of the shell 12, as will be understood, the reference numeral 18 designating the air supply passage. The valve in question is provided with a depending stem 19 which extends through 15 an opening provided in the top wall of a hollow housing 20, which housing provides a guide for the lower end of the valve stem and contains a spring for holding the valve upon its seat, as will hereinafter appear. 20 Said housing is supported from the lower end of the shell by means of arms 21, and the stem of the valve is threaded and carries an internally threaded adjustable sleeve 22 against which the lower end of a spring 23 25 abuts, while the upper end of said spring abuts against the top wall of said housing; so that the air valve will be held to its seat by this spring 23, and will move against the force thereof as it rises from its seat. 30 The exterior of the sleeve 22 is also threaded, and 24 designates an annular adjustable collar the periphery of which is in sliding engagement with the inner surface or side wall of the housing 20, whereby a dash-pot 35 is formed by the collar and hollow housing and within which a body of air is trapped, which air is compressed as the air valve moves upward and acts either independently or in conjunction with the spring 23 to re- 40 turn the said valve to its seat, as will be understood. The collar herein referred to is in threaded engagement with the sleeve 22 as shown, from which it follows that the positions of both the sleeve and collar relative to the valve stem may be varied. A 45 lock nut 25 is preferably provided for securing the sleeve in whatever position it may be placed. The collar 24 in addition to serving as the movable member of a dash- 50 pot as above explained serves also as a support for the lower end of a spring 26 which is normally out of action, but the upper end of which comes into engagement with the upper wall of the housing 20 upon excessive 55 upward movement of the air valve due to the momentum of the valve, or an excessive flow of air past the same, or to other causes, the spring in question thus acting as a buffer under the conditions referred to. 60 The upper end of the shell 12 is made cylindrical as shown at 27, and the portion of the inner wall 6 which lies opposite the upper end of the shell and between the upper end of the conical portion 7 thereof 65 and the carbureting chamber is also cylind-

rical, as shown at 28, and is slightly larger than the cylindrical portion 27, from which it follows that a narrow annular opening is provided between the cylindrical portions herein referred to and that the heated 70 or vaporized liquid fuel passes from the fuel chamber into the carbureting chamber of the carbureter through a narrow annular passage and in a thin annular stream. The annular opening herein referred to is permanently open, as the air inlet valve 17 seats upon the upper end only of the shell 12, and is not large enough in diameter to close said annular opening.

It will be appreciated that the area of the 80 annular opening through which the heated or vaporized liquid fuel enters the carbureting chamber is dependent upon the diameters of the cylindrical portions 27, 28 above referred to, and that such area will 85 remain unchanged so long as these portions overlap one another. It therefore follows that if the shell as a whole is made to occupy a higher or lower position within the carbureter casing than that in which it is 90 illustrated, while the thickness of the film of fuel in the fuel chamber between the said shell and the conical wall 7 will be varied, the area of the annular opening through which the fuel flows into the carbureting 95 chamber will remain constant so long as the cylindrical portions overlap as above pointed out. It follows further that so long as the diameters of the cylindrical portions 27, 28 of the shell and carbureter cas- 100 ing are carefully determined the other dimensions of the parts may vary throughout wider limits, as the diameters in question determine the area of the fuel supply passage which is the feature which should remain fixed in a given carbureter. The ma- 105 chine work upon a carbureter having the feature herein referred to need not therefore be so accurate as would be necessary in a carbureter in which variations in the 110 position of the shell when the parts are assembled are accompanied by corresponding variations in the area of the passage through which the fuel issues into the carbureting chamber. Finally, the provision 115 of a gasket between the flange 13 and the bottom wall of the carbureter casing when the parts are initially assembled, should a gasket be considered necessary or desirable, or the provision of a gasket upon reassem- 120 bling the parts after the shell has been removed should it be found necessary to remove the shell, will not change the area of the fuel supply passage so long as the cylindrical portions of the sleeve and inner wall 125 overlap one another; and, as will be appreciated, variations in the thickness of such a gasket, if one is used, will have no effect upon the area of the fuel supply passage so overlap.

The reference numeral 29 designates a liquid fuel supply chamber to which fuel is supplied through a fuel supply pipe 30 and within which chamber a constant level is maintained as by means of a suitable float controlled valve not herein specifically illustrated and described. This chamber is commonly provided with two compartments as shown in Fig. 2, one of the compartments being designed to receive kerosene and the other gasoline and each compartment having an independent fuel supply pipe leading thereinto, so that the engine may be started by the use of gasoline and operated by kerosene after it and the carburetor have become heated.

A valve chamber 31 is provided upon the under side of the chamber 29, and 32 designates an oscillating valve located in said chamber and having an arm 33 secured to an extending stem 34 of the valve and by means of which arm the valve may be operated and placed in positions such that fuel may flow to the carburetor from either of the compartments of the chamber 29 when the valve is in its extreme positions, and from both said compartments when the valve is in intermediate positions; so that either kind of fuel may be used and, at the same time, the supply of fuel will not be interrupted in changing from one kind of fuel to the other. In order to accomplish this result said valve is provided with a longitudinally extending passage 35, and with two radial passages 36, 37 having recesses 67, 68 at their outer ends; which passages communicate with offset passages 38, 39 leading from the two compartments of the fuel chamber according to the position in which the valve is placed. The valve is provided with a third radial passage which communicates with the passage 35 and with a slot 40 formed in the periphery thereof and which slot is in permanent communication with the fuel supply passage 16 hereinbefore referred to, from which it follows that fuel will always be supplied to the carburetor from one or the other of the compartments of the fuel chamber. The valve herein referred to is preferably conical as shown, and is forced against its seat by a spring 41 surrounding the stem 34 and acting between a collar 42 carried by the valve stem and a washer 43 which bears against the carburetor casing when the parts are assembled, as will be understood.

The flow of liquid fuel through the supply passage 16 is controlled by a suitable controlling valve, preferably in the form of a vertically movable reciprocating regulating valve 44 located within a passage provided in an enlarged portion 45 of the casing of the fuel chamber, and the upper end of which valve is in threaded engagement with a cross-head 46 having parallel sides and

shown as square in cross-section, and having projecting pins at its sides as shown at 47; from which it follows that upon rotating the valve as by means of a milled head 48 it may be adjusted relative to the cross-head 46 to thereby secure a proper supply of liquid fuel to the fuel chamber and a proper proportion of air and fuel in the combustible mixture, after which it is locked in place by means of a lock nut 49. It will be seen that this fuel controlling valve controls the flow of fuel to the fuel chamber of the carburetor and is located at some distance therefrom, as distinguished from being located at and controlling the flow from a discharge passage or nozzle directly into the carbureting chamber; and that there will always be a considerable quantity of fuel in the fuel chamber in open communication with the carbureting chamber through the annular fuel supply passage leading from the fuel chamber and ready to respond to any sudden demand for combustible mixture due, for example, to a sudden opening of the mixture controlling or throttle valve 50 hereinafter referred to.

The cross-head 46 lies between two lifting cams 50 secured upon an oscillating shaft 51 supported in brackets 52 shown as supported upon the cover of the fuel chamber 29, the working faces of said cams being in engagement with the pins 47 carried by the cross-head, as shown in Figs. 1 and 3. It follows because of this location of the cross-head between the cams 50 that the cams prevent the cross-head from rotating with the fuel valve when the latter is rotated to adjust it relative to the cross-head to thereby regulate the amount of fuel in the mixture, or the richness of the mixture, as hereinbefore pointed out.

The oscillating shaft 51 carries an arm 53 at its free end, and 54 designates a link connecting the free end of this arm with an arm 55 upon the free end of a second oscillating shaft 56 which last mentioned shaft carries a throttle valve 57 located in the combustible mixture passage 58 leading from the carburetor to the engine. The oscillating shaft 56 is operated through an arm 59 secured thereto and which arm in turn is connected in any way with a suitable lever or other device so located as to be conveniently accessible to the operator of the automobile with which the carburetor is designed for use; from which it follows that movement imparted to the valve shaft 56 will be transmitted to the cam shaft 51, and that the throttle valve 57 and fuel valve 44 will be operated simultaneously, the arrangement of the parts being such that the supply of fuel is reduced as the flow of combustible mixture to the engine is throttled, and vice versa.

The improved carburetor hereinbefore de-

scribed is preferably used in connection with means for supplying a small quantity of water to the combustible mixture as it flows to the engine, and one of the objects of my 5 invention is to provide a water supplying device which may readily be included in a line of piping leading from the carbureter to the engine, to be as readily removed therefrom if it is not desired to feed water to the 10 mixture, in either case with a minimum of trouble and without disturbing the mixture supply conduit, the carbureter, or its connections, to any considerable extent. This water supplying device comprises a water chamber 15 60 to which water is supplied through a pipe 61 and within which chamber a constant level of water is maintained by a float controlled valve, as will be understood. Connected with this water chamber so that the 20 62 will form a single unitary device or structure is a member, shown as being in the form of a flange 62, designed to be connected and included in the line of piping 65 leading to the engine, and which member in fact 25 forms a part, although preferably but a small part, of the mixture supply conduit. This member is provided with an opening 63 adapted to register with the passage 58 and the piping 65, and the water chamber 30 and connecting member are provided with a passage 64 discharging into the opening 63 and having a regulating valve 66, to thus supply water to the combustible mixture as it flows to the engine, as will be understood. 35 It will be seen that in initially installing a carbureter the water supplying device may or may not be provided, as desired; and that if it is subsequently decided to install or to remove the water supplying device the 40 conduit section 65 may be disconnected from the carbureter casing as by removing the screws or other fastening means whereby it is held in place, the water supplying device put in place or removed, and the parts 45 again secured together, all by loosening one only of the joints in the mixture supply conduit and without disturbing the carbureter or its connections to any material extent.

While the water supplying device is illustrated and the above description refers to the same as being interposed between the carbureter casing and the beginning of the conduit leading to the engine, it will be understood that the same may be readily introduced into the mixture supply conduit at any place where two sections thereof are detachably secured together, and, if introduced at such a point may be as readily removed in the same manner as above explained.

Having thus described and explained my invention, I claim and desire to secure by Letters Patent:

1. In a carbureter for internal combustion engines, a casing having outer and inner walls

spaced apart from one another to thereby provide an intervening heating chamber, the lower portion of said inner wall being conical in form, the upper portion thereof being shaped to provide a carbureting chamber, 70 and an intermediate portion of said wall being cylindrical; a hollow conical shell located within the conical portion of said inner wall and spaced apart therefrom to thereby provide an annular fuel chamber, 75 and the upper end of which shell is cylindrical and lies within and is spaced apart from the cylindrical portion of said inner wall and is provided with a valve seat; and an air inlet valve resting upon said valve seat, 80 said casing being provided with a passage through which a liquid fuel may be supplied to said fuel chamber.

2. In a carbureter for internal combustion engines, a casing having outer and inner walls spaced apart from one another to thereby provide an intervening heating chamber, the lower portion of said inner wall being conical in form, the upper portion thereof being shaped to provide a carbureting chamber, 90 and an intermediate portion of said wall being cylindrical; a hollow conical shell located within the conical portion of said inner wall and spaced apart therefrom to thereby provide an annular fuel chamber, 95 and the upper end of which shell is cylindrical and lies within and is spaced apart from the cylindrical portion of said inner wall and is provided with a valve seat; a hollow housing supported from the lower end of said shell; an air inlet valve resting upon said valve seat and having a depending stem extending through the housing aforesaid; and a spring located within said housing and acting upon said valve to hold it upon its seat, said casing being provided with a passage through which a liquid fuel may be supplied to said fuel chamber.

3. In a carbureter for internal combustion engines, a casing having outer and inner walls spaced apart from one another to thereby provide an intervening heating chamber, the lower portion of said inner wall being circular in cross-section and the upper portion thereof being shaped to provide a carbureting chamber; a hollow shell circular in cross-section located within the lower portion of said inner wall and spaced apart therefrom to thereby provide an annular fuel chamber, and the upper end of 110 which shell is provided with a valve seat; a hollow housing supported within the lower portion of said shell; an air inlet valve resting upon said valve seat and having a depending stem extending through the top wall of said housing; an abutment carried by said valve stem and which abutment moves in contact with the side wall of said housing; and a spring located within said housing and acting between the top wall 115 120 125 130

- thereof and said abutment to hold said valve upon its seat, said casing being provided with a passage through which liquid fuel may be supplied to said fuel chamber.
5. 4. In a carbureter for internal combustion engines, a casing having outer and inner walls spaced apart from one another to thereby provide an intervening heating chamber, the lower portion of said inner wall being conical in form and the upper portion thereof being shaped to provide a carbureting chamber; a hollow conical shell located within the conical portion of said inner wall and spaced apart therefrom to thereby provide an annular fuel chamber, and the upper end of which shell is provided with a valve seat; a hollow housing supported from the lower portion of said shell; an air inlet valve resting upon said valve seat and having a depending stem extending through the top wall of said housing; an abutment carried by said valve stem; and a spring located within said housing and acting between the top wall thereof and said abutment to hold said valve upon its seat, said casing being provided with a passage through which a liquid fuel may be supplied to said fuel chamber.
5. In a carbureter for internal combustion engines, a casing having outer and inner walls spaced apart from one another to thereby provide an intervening heating chamber, the lower portion of said inner wall being conical in form and the upper portion thereof being shaped to provide a carbureting chamber; a hollow conical shell located within the conical portion of said inner wall and spaced apart therefrom to thereby provide an annular fuel chamber, and the upper end of which shell is provided with a valve seat; an air inlet valve resting upon said valve seat and having a depending stem; a guide supported from the lower end of said shell and having an opening through which said stem extends; and a spring for holding said valve upon its seat, said casing being provided with a passage through which a liquid fuel may be supplied to said fuel chamber.
50. 6. In a carbureter for internal combustion engines, a casing having outer and inner walls spaced apart from one another to thereby provide an intervening heating chamber, the lower portion of said inner wall being conical in form and the upper portion thereof being shaped to provide a carbureting chamber; a hollow conical shell located within the conical portion of said inner wall and spaced apart therefrom to thereby provide an annular fuel chamber, and the upper end of which shell is provided with a valve seat; a hollow housing supported within the lower portion of said shell; an air inlet valve resting upon said valve seat and having a depending stem ex-
- tending through the top wall of said housing; a sleeve in threaded engagement with said valve stem; a spring surrounding said valve stem and the ends of which abut against said sleeve and the top wall of said housing; a collar in threaded engagement with said sleeve and which collar moves in contact with the side wall of said housing; and a second spring surrounding said first mentioned spring and the lower end of which rests upon said collar, said casing being provided with a passage through which a liquid fuel may be supplied to said fuel chamber.
7. In a carbureter for internal combustion engines, a casing having outer and inner walls spaced apart from one another to thereby provide an intervening heating chamber, the lower portion of said inner wall being circular in cross-section and the upper portion thereof being shaped to provide a carbureting chamber; a hollow shell circular in cross-section located within the lower portion of said inner wall and spaced apart therefrom to thereby provide an annular fuel chamber, and the upper end of which shell is provided with a valve seat; a conduit located within and extending across the carbureting chamber aforesaid and the ends of which communicate with said heating chamber; and an air inlet valve resting upon said valve seat, said casing being provided with a passage through which a liquid fuel may be supplied to said fuel chamber.
8. In a carbureter for internal combustion engines, a casing having a carbureting chamber, air and fuel supply passages leading to said chamber, and a mixture passage leading therefrom; a reciprocating fuel valve for controlling the flow of fuel through said fuel passage; an oscillating cam shaft; a cam carried by said shaft; means intermediate said cam and fuel valve and through which said valve is operated by said cam; an arm carried by said cam shaft; an oscillating mixture valve for controlling the flow of combustible mixture through said mixture passage; means for operating said valve; an arm connected with said valve so as to move therewith; and a link connecting said arm with the arm aforesaid upon said cam shaft.
9. In a carbureter for internal combustion engines, a casing having a carbureting chamber, air and fuel supply passages leading to said chamber, and a mixture passage leading therefrom; a reciprocating fuel valve for controlling the flow of fuel through said fuel passage; an oscillating cam shaft; two cams carried by said shaft and spaced apart from one another; a cross-head located between said cams and having parallel sides so that the cams prevent the cross-head from rotating, and with which

- 6
- cross-head said fuel valve is in threaded engagement; two pins carried by said cross-head and with which said cams engage; an arm carried by said cam shaft; a mixture 5 valve for controlling the flow of combustible mixture through said mixture passage; an oscillating valve shaft for supporting said valve; an arm carried by said valve shaft; a link connecting the arm upon said valve 10 shaft with the arm upon said cam shaft; and means for operating said valve shaft.
10. In a carbureter for internal combustion engines, a casing having outer and inner walls spaced apart from one another to 15 thereby provide an intervening heating chamber, the lower portion of said inner wall being circular in cross-section and the upper portion thereof being shaped to provide a carbureting chamber; a hollow shell 20 circular in cross-section located within the lower portion of said inner wall and spaced apart therefrom to thereby provide an annular fuel chamber, and the upper end of which shell is provided with a valve seat; 25 a hollow housing supported within the lower portion of said shell; an air inlet valve resting upon said valve seat and having a depending stem extending through the top wall of said housing; an abutment carried 30 by said valve stem and which abutment moves in contact with the side wall of said housing; and a conduit through which liquid fuel may be supplied to said fuel chamber.
- 35 11. In a carbureter for internal combustion engines, a casing having outer and inner walls spaced apart from one another to thereby provide an intervening heating chamber, the lower portion of said inner 40 wall being conical in form and the upper portion thereof being shaped to provide a carbureting chamber; a hollow conical shell located within the conical portion of said inner wall and spaced apart therefrom to
- thereby provide an annular fuel chamber, 45 and the upper end of which shell is provided with a valve seat; a hollow housing supported from the lower portion of said shell; an air inlet valve resting upon said valve seat and having a depending stem extending 50 through the top wall of said housing; an abutment carried by said valve stem and the periphery of which moves in contact with the inner surface of said housing; and a 55 conduit through which liquid fuel may be supplied to said fuel chamber.
12. In a carbureter for internal combustion engines, a casing having outer and inner walls spaced apart from one another to thereby provide an intervening heating 60 chamber, the lower portion of said inner wall being circular in cross-section and the upper portion thereof being shaped to provide a carbureting chamber; a hollow shell 65 circular in cross-section located within the lower portion of said inner wall and spaced apart therefrom to thereby provide an annular fuel chamber, and the upper end of which shell is provided with a valve seat; an air inlet valve resting upon said valve 70 seat; a fuel supply conduit through which a liquid fuel may be supplied to said fuel chamber; a valve for controlling the flow of fuel through said conduit; a combustible mixture conduit leading from said carbureting chamber; a mixture controlling valve for controlling the flow of combustible mixture through said mixture conduit; and means intermediate said mixture and fuel 75 valves and through which movement is transmitted from one to the other.
- In testimony whereof I have signed my name to this specification in the presence of two subscribing witnesses.

Washington, D. C."

Correction in Letters Patent No. 1,176,816.

It is hereby certified that in Letters Patent No. 1,176,816, granted March 28, 1916, upon the application of Wade Hampton de Fontaine, Jr., of Perth Amboy, New Jersey, for an improvement in "Kerosene-Carbureters," an error appears in the printed specification requiring correction as follows: Page 2, after line 129 insert the words *long as the cylindrical portions aforesaid*; and that the said Letters Patent should be read with this correction therein that the same may conform to the record of the case in the Patent Office.

Signed and sealed this 18th day of April, A. D., 1916.

[SEAL.]

R. F. WHITEHEAD,

Acting Commissioner of Patents.
